UNITED STATES PATENT OFFICE.

EARL V. HILL, OF CHICAGO, ILLINOIS.

DUST-COUNTER.

1,274,415.

Specification of Letters Patent. Patented Aug. 6, 1918.

Application filed February 5, 1917. Serial No. 146,639.

To all whom it may concern:

Be it known that I, EARL V. HILL, a citizen of the United States, residing at Chicago, county of Cook, and State of Illinois, have invented certain new and useful 5 Improvements in Dust-Counters, of which the following is a specification.

My invention relates more particularly to an apparatus for counting or approximating the number of particles of solid matter contained in a given volume of air. The instrument is useful in a variety of connections but was designed more particularly with reference to the science of ventilation 10 in which it is important to know, among other things, the extent of contamination by solid particles of various kinds in the form of dust. The apparatus is further useful 15 for the purpose of ascertaining the number of bacteria contained in a given quantity of air, a slight modification of the device being made for this purpose.

In the accompanying drawing I have shown and in the following specification described in detail a preferred form of the apparatus with attachments to be used for counting dust and bacteria respectively. It is to be understood, however, that the specific disclosure is for the purpose of 20 amplification only, and that the scope of the invention is defined in the following claims in which I have endeavored to distinguish it from the prior art so far as known to me without, however, relinquishing or abandoning 25 any portion or feature thereof.

In the drawings Figure 1 is a longitudinal section of a preferred form of my invention, comprising a form of attachment particularly adapted for counting dust particles; 30 Fig. 2 a transverse section on the line 2—2 of Fig. 1; and Fig. 3 an axial section through an attachment to be used with the device for counting bacteria.

The main element of my dust counter is 35 a pump which is adapted to draw in and discharge a definite measured quantity of air, the particular construction thereof being unimportant provided it fulfills the above condition. In the particular form shown the 40 pump comprises a barrel 4 having a cap 5 which has an axial bore 6 for the passage of the hollow piston stem 7. The latter has a handle 8 outside the cylinder and at the other end of the piston 9 with a packing 10 held 45 between the body of said piston and a screw plug 11, the flange 12 of which overlaps said

packing. The plug 11 has a reduced head 13 through which extends the passage 14 and upon which is secured a flexible valve 15 which may be made of oiled silk or other 50 suitable material. The intake end of the cylinder is provided with a head 16 perforated at 17 for the passage of air, and extended at 18 to form a seat for the flexible valve 19. The outer end of the cap piece 16 55 is interiorly threaded at 20 to receive a coupling member 21 which is formed with a nipple 22 to receive an attachment presently to be described. While the form of pump just described is well adapted for the 60 purpose, any other approved type will answer provided it is so constructed that the attachments may be readily mounted thereon, and it is adapted to take in a measured quantity of air.

The attachment to be used for the purpose of counting dust consists of a casing or chamber *a*, the bottom wall 23 being perforated at 26 in line with the passage 24 of the connection 21, and interiorly threaded at 25 to receive the nipple 22. The wall 23 is shouldered and threaded at 27 to receive the cup 28, and the latter is formed with an axial perforation 29 extending through internal and external bosses 30, 31 formed integral with said cup. Within the chamber post 32 is mounted upon the bottom wall 23 and carries a pair of spring arms 33, 33 which, as well as the post, are notched at 34 their ends as at 34, to receive a thin disk of 75 glass 35, such as are commonly employed as cover plates for microscope slides.

When the device is to be used for counting dust a glass disk is covered upon one side with a sticky substance which may be 80 Canada balsam, or a mixture of Damar varnish and glycerin, nine parts of the former to one of the latter. The disk is then inserted in the support or holder, as 85 shown in the drawing, with the sticky side toward the inlet 29 of the chamber. The pump is then operated to completely fill the cylinder thereof, the capacity of which is known. This operation draws in a definite 90 quantity of air through the opening 29 projecting it against the sticky material upon the disk, to which the greater number of 95 motes or dust particles in the air adhere. It may readily be determined by a method hereinafter described what proportion of 100 the entire number of dust particles in the air are captured by the sticky material on 105 110

the plate, and, the amount of air passing through the chamber being known, the entire number of particles per unit of air can be readily calculated.

- 5 In order to determine what proportion of the dust particles is extracted from the air passed through the counting chamber in this way, I mount two or more of the chambers *a* in series upon the pump. In the 10 drawing I have shown in dotted lines a second chamber mounted on the pump but for more accurate work I may use a greater number, the larger the number used the more accurate the results, as will be evident.
- 15 The external bosses 31 on the chambers are of a size and threaded to fit the threads 27 in the bottoms of the chambers, thus providing an easy method of mounting the chamber in series by screwing each successive chamber on the boss of the preceding chamber. When the series of chambers is in place upon the pump and each chamber containing its glass disk coated with adhesive the pump is operated to draw in a full 25 charge so that a certain definite amount of air passes successively through each chamber. The larger proportion of the motes or solid particles in the air is removed in the first chamber but a certain proportion of the 30 motes escapes, a large proportion of these is caught in the second chamber, and so on. Obviously by noting the decline in the number of dust particles caught on the successive disks, by a process of extrapolation 35 the number of particles remaining in the air can be closely approximated and by adding the results on the successive disks the entire number of particles in the air may be compared with those caught upon the first 40 disk and the efficiency of the single chamber thus determined. After having made this determination or calibration of the instrument it is only necessary thereafter to use a single chamber and by calculation determine 45 the entire number of dust particles per unit of volume in any sample of air.
- 50 Preferably an adhesive is used which while remaining moist or tacky long enough to be properly charged will dry within a convenient length of time retaining the particles. It is convenient to mount the disks on the usual microscope slides with the adhesive containing the dust sealed between the disk and the slide. The counting of course 55 will be done by the aid of a microscope.
- 60 When the bacteria in a sample of air are to be counted, in place of the glass disk referred to, I use what is known as a Petrie dish containing a suitable medium for bacteria culture. In Fig. 3 I have shown a modification of the chamber for the use of the Petrie dish, the only essential modifications being in point of size. The chamber 65 is considerably larger in order to accommodate the Petrie dish 35' and the post 32' and

the spring arms 33', 33' are correspondingly modified to form a support for the dish. For the purpose of counting bacteria the use of the apparatus is identically the same as described in connection with the determination of dust particles, but after the pump has drawn the required charge of air through the chamber the culture is incubated at room temperature the requisite length of time and the bacterial colonies that develop are then counted to determine the number of original bacteria caught by the dish. The entire number of colonies may then be calculated as above described in connection with dust counting.

I claim:

1. In a device of the class described, a reciprocating pump for drawing in and discharging a definite charge of air, a chamber in operative connection with the cylinder of the pump, a support within the chamber and a disk stationarily mounted on the support and having adhesive thereon in the path of the current of air for arresting particles of solid matter.

2. In a device of the class described, a reciprocating pump for drawing in and discharging a definite charge of air, a chamber detachably mounted on the pump and communicating therewith and with the outer air, and a support within the chamber for removably holding a disk having adhesive thereon in the line of travel of the air from the inlet to the pump.

3. In a device of the class described, a pump, a chamber detachably mounted on the pump, having communication with the latter, an inlet opposite said communication and a spring support intermediate the inlet and communication for supporting a disk having adhesive thereon in the line of travel of the air.

4. In a device of the class described, a pump, a dust separation chamber comprising a base having means for detachably connecting it to the pump, a cup detachably connected to the base and a support for a disk having sticky matter thereon mounted in said chamber.

5. In a device of the class described, an air pump adapted to draw in and discharge a predetermined definite charge of air, a series of chambers connected to the air pump there being series communication between the pump and chambers such that the charge of air drawn in by the pump passes successively through the chambers, and similar means in each of the chambers for arresting particles of dust contained in the air.

6. In a device of the class described a pump, a dust separation chamber attached to the pump, a disk having sticky matter thereon and means detachably supporting said disk in the chamber.

7. In a device of the class described, a

pump, a dust separation chamber attached to said pump and communicating with the cylinder thereof, one of the walls of said chamber being detachable for access to the 5 interior thereof, means within the chamber for detachably holding a disk, and a disk on said means having adhesive thereon.

8. In a device of the class described a

pump, a dust separation chamber mounted on the pump and communicating with the 10 cylinder thereof, said chamber having a removable wall, a disk support mounted on said wall, and a disk detachably mounted on said support.

EARL V. HILL.
